(57) **CLAIM**

The ornamental design for a clamping level tool, as shown and described.

DESCRIPTION

FIG. 1 is a top front perspective view of my new, original and ornamental design for a clamping level tool;

FIG. 2 is a front elevation view thereof, the rear elevation view being a mirror image thereof;

FIG. 3 is a top plan view thereof;

FIG. 4 is a bottom plan view thereof;

FIG. 5 is a front end view thereof; and,

FIG. 6 is a rear end view thereof.

The broken lines are for illustrative purposes only and form no part of the claimed design
